AUTOMATIC BOILER WASHER

William L. Pearce, Houston, Tex.

Application October 18, 1938, Serial No. 235,558

1 Claim. (Cl. 122—405)

This invention relates to a boiler washer.

In the operation of boilers for generating steam foreign matter accumulates in the water chamber about the fire box and furnace and heretofore it has been necessary, in order to remove said clogging material, to extinguish the fire, drain out the water and manually remove the clogging material.

It is a prime object of the present invention to provide means whereby the clogging material, so collected, may be readily flushed out and thus removed from the water chamber of the boiler.

It is another object of the invention to provide a device of the character described whereby the flushing operation, for removing said clogging material, may be carried on while the boiler is in use thus not interfering with the operation of the boiler.

It is a further object of the invention to provide a flushing, or washing attachment which may be readily applied to, or removed from, a conventional type of boiler, which may be cheaply constructed and is very efficient in use.

A still further object of the invention resides in a novel method whereby all clogging material accumulating in the water chamber about the boiler furnace may be quickly, easily, and thoroughly removed.

With the above and other objects in view the invention has particular relation to certain novel features of construction, operation and arrangement of parts and to a novel method, an example of which is given in this specification and illustrated in the accompanying drawings, wherein:

Figure 1 shows a front, elevational view showing a battery of boilers with the washing equipment applied thereto.

Figure 2 shows a vertical, sectional view taken on the line 2—2 of Figure 1.

Figure 3 shows an enlarged, fragmentary, cross-sectional view taken on the line 3—3 of Figure 1, and

Figure 4 shows an enlarged, fragmentary, cross-sectional view taken on the line 4—4 of Figure 1.

Referring now more particularly to the drawings, wherein like numerals of reference designate similar parts in each of the figures, the numeral 1 designates a boiler of conventional construction, three being shown in Figure 1. Each boiler has a fire box, or furnace, 2 as illustrated in Figure 2. As shown in Figure 1 the steam domes 3 of the boilers have the steam pipe 4 connected thereto for the conduct of the steam to the engine or other point of utilization. The water chamber 5 of each boiler surrounds the

furnace 2 and scale and other clogging material gradually collects in said water chamber and interferes with the circulation of the water therethrough causing the walls of the furnace to burn out unless the clogging material be from time to time removed.

The parts hereinabove referred to are of conventional construction but novel equipment has been provided for washing or cleansing the water chamber and which will now be described.

The numeral 6 designates a manifold pipe which extends transversely of the battery of boilers and into which a supply pipe 7, leading from a suitable pump, is connected. Water supply lines 8 lead from the manifold and are connected into the ends of the respective boilers remote from the furnace and these pipes 8 are controlled by the respective shut off valves 9.

Tubular water legs 10, 10 are connected into the manifold 6 there being one pair of legs 10 for each boiler. Each pair of legs 10 merge into a common nozzle pipe which is inwardly turned through the front wall of the boiler above the crown sheet of the furnace. On the inner end of the inwardly turned nozzle pipe 11 there is a nozzle 12 having the diverging outlets through which water is sprayed in a fanlike sheet across the top of the crown sheet and said nozzle 12 has a downwardly directed nozzle opening 13 through which the water is forced downwardly between the front wall of the furnace and the front wall of the boiler as more clearly illustrated in Figure 2.

Each leg 10 also has an inwardly directed nozzle pipe 14 which extends through the front wall of the boiler on opposite sides, and beneath the fire box, or furnace, and these nozzle pipes 14 terminate in the nozzles 15.

As more clearly illustrated in Figure 3 each nozzle 15 has the oppositely arranged, transversely disposed outlet openings through which the washing fluid is emitted in each direction parallel with the front wall of the boiler and each nozzle 15 has a discharge opening arranged axially with respect to the nozzle pipe 14 and through which the washing fluid is discharged in a direction parallel with the walls of the boiler.

The nozzle pipes 11 and 14 extend through the respective cover plates 16 and 17, 17. The nozzle pipes are threaded through the respective cover plates as shown. The margins of the cover plates engage against the inner side of the front wall of the boiler completely around the openings to be closed thereby and arcuate clamps 18 and 19, 19 have central bearings through which the

respective nozzle pipes 11, 14 extend and clamp nuts 20, 21, 21 are threaded onto said respective nozzle pipes and clamp against the corresponding clamps 18, 19 whereby to secure said cover plates 16, 17 in place.

Each water leg 10 is equipped with a shut off valve as 22. These valves 22 are closed during the normal operation of the boilers. Each chamber 5 is provided with a drain pipe 23, at its lower end which is normally closed by the valve 24.

When it is desired to flush out and cleanse the chamber 5 of any boiler the steam line leading from said boiler may be closed or cut off by closing the corresponding valve as 25. The valve 24 and the valves 22 of said boiler may then be opened. A flushing fluid, under pressure, will thus be supplied into the boiler beneath, and in front of as well as along the sides of the furnace 20 or fire box, by the nozzles 15 and will be supplied across the crown sheet of the fire box and in front of said fire box by the nozzle 12, the clogging material draining out through the drain pipe 23.

In some cases it may be desired to maintain the boiler in operation while the cleansing process is being carried on and in such event the valve 25 will be allowed to remain open and the corresponding valve 9 may be opened or partly opened

so as to keep the boiler being cleansed supplied with the necessary quantity of water for that purpose to the end that the flushing fluid may be supplied to and relieved from the water chamber about the fire box without abnormally disturbing the level of the water about the tubes of the boiler.

The drawings and description disclose what is now considered to be a preferred form of the invention by way of illustration only, while the broad principle of the invention will be defined by the appended claim.

What I claim is:

A washer for a boiler having a water chamber surrounding the fire box of the boiler and comprising nozzles anchored to the forward wall of the boiler, one on each side of and beneath the fire box and one arranged above the crown sheet of the fire box, each nozzle having spray nozzle openings adapted to spray a washing fluid in mutually perpendicular planes, said upper nozzle being positioned to discharge said fluid on top of and on the forward wall of the fire box to wash above and in front of the fire box and the lower nozzles being positioned to discharge said fluid below the fire box, to thereby wash beneath firebox and means for supplying washing fluid to the nozzles for performing said washing operations simultaneously.
